TELEPHONE COUPLER

Charles Jerabek, Bayshore, N.Y., assignor to Vernitron Corporation, Farmingdale, N.Y., a corporation of New York

Filed Nov. 24, 1967, Ser. No. 9,547

Term of patent 14 years

(Cl. D26—14)

Fig. 1.

Fig. 3.

Fig. 4.

Fig. 2.

FIG. 1 is a front perspective view of a telephone coupler showing my new design;

FIG. 2 is a front elevational view thereof;

FIG. 3 is a right side elevational view thereof; and

FIG. 4 is a top view thereof.

The base, not shown, is conventional, and the side opposite that shown is substantially the same as the side which is shown. The lower part of the rear side is planular.

I claim:

The ornamental design for a telephone coupler, substantially as shown and described.
